RAPID OPERATION AIR LOCK FOR
CLOSED VESSELS

Robert T. Avery, Oakland, Calif., assignor to
United States of America as represented by the
United States Atomic Energy Commission

Application September 5, 1952, Serial No. 307,977

7 Claims. (Cl. 214—17)

1

This invention relates to the apparatus of the type known as air locks, such structures providing access chambers adjacent closed vessels. More particularly, the invention is concerned with air lock means for use with the vacuum vessels of mass spectrometers or the like. In the operation of the latter, it is frequently desired to transfer an object from the exterior to the interior of the vacuum chamber without contaminating the vacuum with air. A typical procedure is the introduction of a small sample of a radiation-emitting substance into a mass spectrometer vacuum chamber to enable a study to be made of the characteristics of the radiation.

A principal factor in the foregoing operation is the time element. That is, when employing a substance whose radiation-emitting ability rapidly diminishes over a short interval of time, it is essential that the time required to introduce the substance into the chamber be as short as possible.

Prior to the present invention, so far as I am aware, devices for facilitating the foregoing operation have generally utilized a plurality of compression tap valves and manually operated seals. The time consuming manipulation of such controls despite optimum conditions was a serious disadvantage. To overcome the numerous shortcomings of the arrangements referred to and to reduce the time element mentioned were the desiderata resulting in the present invention.

Broadly stated, the latter provides a chamber or air lock sealingly secured to the apertured wall of a vacuum chamber of the type referred to and including a spring-pressed closure which is movable into sealing contact with the wall portion defining said aperture and having also a position of translation away from and to one side of said aperture whereby the use of a probe for carrying the radiation-emitting substance axially of the aperture into the interior of the evacuated vessel is facilitated.

It is more especially an object of the invention to provide air lock apparatus providing a completely unobstructed opening into the vacuum chamber.

Another object of the invention is to provide in an air lock apparatus an aperture closure plate having uniform peripheral sealing pressure.

Another object is to provide air lock apparatus in which the flexible sealing elements, such as gaskets for the necessary movable parts of the air lock, are of such configuration as to pre-

2

vent excessive wear or unusual deformation during long use thereof.

Yet another object of the invention is to provide air lock apparatus which is readily detachable from the vacuum chamber.

An additional object of the invention is to provide in an air lock apparatus, an integral wall structure incorporating a probe guide which not only insures accurate alignment of the latter 10 through all positions thereof, but materially speeds up the manual insertion and withdrawal of the latter.

A still further object of the invention is to provide an air lock apparatus characterized by 15 rugged construction and quick operation and one that involves both a minimum of first cost and insignificant service expense and servicing time.

For a better understanding of the preferred 20 form of the air lock of this invention, reference is now made to the accompanying drawing wherein:

Figure 1 is a cross section view of the invention showing also associated apparatus;

25 Figure 2 is a cross section view taken on the line 2—2 of Figure 1, and

Figure 3 is a perspective view of a vacuum chamber equipped with the improved air lock.

Referring to the drawing, there is shown at 5 30 the wall of a vacuum vessel which may be that of a mass spectrometer, for example, having an aperture 6 which may be closed by a closure plate 7 disposable thereacross and also movable laterally thereof by means later to be described herein. Surrounding closure plate 7 and mounted on the wall 5 by means such as bolts 8 extending through ears 9 is an air lock housing structure 11 of generally box-like configuration having an open side coplanar with the outer surface 40 of wall 5 as are ears 9 which are integral with said housing.

Housing 11 which is preferably made as an integral casting includes an outwardly extending tubular portion 12 of substantial length having 45 an inner cylindrical bore 13 in alignment with aperture 6 of the vacuum vessel. An end wall 14 of housing 11 remote from bore 13 and extending in a generally normal direction to the open side of the housing is provided with a threaded opening receiving an axially elongated sleeve 15 serving as a bearing for a closely fitting shaft 16 therein. The latter is sealed against the admission of air into the housing 11 by means of a plurality of chevron type seals 17, 55 well known in the art, which seals are retained

by a suitable gland nut 18 threaded interiorly and adjacently into the annular recess wherein seals 17 are seated. Gland nut 18 by virtue of its axial elongation provides a substantial bearing for shaft 16 supplementing the similar action of sleeve 15.

Reference is now made particularly to Fig. 2 for an understanding of the actuating mechanism interconnecting shaft 16 and closure plate 7, which is effective to seal aperture 6, as well as to move such closure plate away from said aperture and thereafter translate the same to a position entirely to one side thereof of aperture 6. It will be seen that in the closed position of the air lock an eccentrically disposed end portion 19 of shaft 16 engages an end wall 20 of housing 11 opposite wall 14 serving as a terminal stop for shaft 16 when the latter is in such position. A generally rectangular follower block 21 having a generally elliptical slot 22 extending between the opposite faces thereof along an axis parallel to the axis of shaft 16 serves as a closed cam surface. Slot 22 surrounds portion 19 of shaft 16 being retained thereon by the terminal shoulder of shaft 16 adjacent thereto and by means such as an annular flange 23, which may be suitably secured to shaft 16 adjacent follower block 21. The latter is united to closure plate 7 by means such as a pair of bolts 24 passing through such block and threaded into closure plate 7, one bolt being on each side of slot 22 and aperture 6, as shown in Fig. 2. By enlarging for a substantial distance the bores in follower block 21 through which bolts 24 extend, recesses facing closure plate 7 are provided wherein compression springs 25 surrounding said bolts may be disposed to exert separative pressure between the follower block and closure plate. This spring action may be varied through the adjustment of lock nuts 26 threaded onto the portions of bolts 24 which extend outwardly from the follower block, as will be readily apparent. Through the provision of a peripheral gasket 27 disposed in a suitable recess in the surface of closure plate 7 facing the wall 5 of the vacuum vessel, it will be seen that an extremely effective seal of equalized peripheral pressure over the opening 6 is attained.

From the immediately preceding description it will be apparent that rotation of shaft 16 in either direction from its position in Fig. 2 corresponding to complete closure of opening 6 will result in movement of follower block 21 and also closure plate 7 away from said opening; thereafter shaft 16 may be pulled to the right until it reaches its extreme position in which the end of the closure plate is stopped against end wall 14 providing complete unobstruction of aperture 6. Such rotation and translation of shaft 16 is conveniently provided by means outside the air lock housing such as a lever 28 secured to the outer end of shaft 16.

An important provision of the invention resides in the substantial axial extent of tubular portion 12 defining correspondingly elongated bore 13. As shown in Fig. 1, an elongated cylindrical probe 32 of diameter corresponding to the diameter of bore 13 and sealed effectively by an appropriate sealing ring 29 seated in an annular recess in such bore, insures continuous alignment of the probe with aperture 6 as the former is projected into a position within the evacuated vessel. The definite terminal positioning of the probe inwardly of the wall 5 is assured through the provision on the probe of a shoulder 30 of increased diameter, a semi-circular cutout 31

corresponding to the smaller or bore diameter of the probe and fitting thereagainst when the bifurcated strip or ball 33 pivotally connected to each side of the tubular portion 12 and providing such cut-out is suitably adjusted. An elongated slot 34 in each leg of the bail forming the continuation of the pivoting apertures thereof permit the bail to be swung upwardly out of the way when it is desired to fully insert the probe. It will be seen that the ball in its indexing position, shown in Fig. 1, definitely indicates the withdrawn position of the probe immediately outside the air lock.

Another opening 35 into the housing 11 and preferably in end wall 20 thereof is provided for the connection of a remotely disposed vacuum pump (not shown) through conduit 36 and intermediate shut-off valve 37 connected to housing 11 by elbow 38. Inasmuch as in practice it is customary to employ a vacuum pump connected to the conduit 36 which is of lower effectiveness than the pumps connected to evacuate the main vacuum vessel and its continued operation while the aperture 6 is open would result in the backing up of air through the air lock pump and into the main vacuum tank with impairment of the vacuum therein, it is preferred to provide on the shaft 16 a contact actuator 39 which moves in such a position on rotary movement of lever 28 as to open a suitable switch 40 and thereby discontinue operation of the pump connected to the air lock.

The operation of the improved air lock is believed to be apparent from the foregoing description, as well as the manifold advantages of operation accruing from the unique arrangement of component parts. Upon partial rotation of lever 28 through a predetermined angle which may conveniently be that which accomplishes opening of switch 40, the latter thereby serving as a stop, the lever 28 is thereafter pulled to the right as far as it will go. With the air lock vacuum pump disconnected the probe having the radioactive substance thereon indicated at 41 may be immediately projected across the width of the air lock, through the aperture 6, and into the tank to a position definitely fixed by the shoulder 30 abutting against the proximate end of tubular portion 12. The operation of withdrawing the probe from the tank and immediately sealing off aperture 6 thereafter is accomplished with similar expedition.

Although the present invention has been disclosed with respect to a preferred embodiment it will be appreciated by those skilled in the art that numerous modifications and variations are possible within the spirit and scope of the invention and it is therefore not desired to limit the invention to the exact details described as may be defined in the following claims.

What is claimed is:

1. Air lock apparatus adapted to be sealingly disposed across an aperture in the planar wall of a vacuum vessel for providing access to the interior thereof under a plurality of vacuum conditions, said apparatus comprising a generally rectangular open-sided housing, an elongated, tubular portion in said housing opposite said open side and in alignment with said wall aperture when said housing is in place, a closure plate for said wall aperture, and manually operable means extending through another wall of said housing and connected to said closure plate for moving the latter normally to said planar wall and into closed position across said wall

aperture and for moving said closure plate normally away from said wall aperture and thereafter laterally thereof to provide complete unobstruction of the latter.

2. The combination of elements defined in claim 1 and wherein said means comprises an elongated bearing secured in said housing on one side of said closure, an elongated, eccentric shaft having a major portion thereof journaled in said bearing and a resilient seal disposed in said bearing and surrounding said shaft.

3. The combination of elements defined in claim 1 and including a vacuum pump connected to said housing for evacuating the same and an electric switch for said pump disposed adjacent said means and operable by the latter for automatically stopping said pump whenever said closure plate is opened by said means.

4. Air lock apparatus adapted to be sealingly disposed across an aperture in the planar wall of a vacuum vessel for providing access to the interior thereof under a plurality of vacuum conditions, said apparatus comprising a generally rectangular open-sided housing, an elongated, tubular portion in said housing opposite said open side and in alignment with said wall aperture when said housing is in place, a closure plate for said wall aperture, and a rigid shaft extending through another wall of said housing and resiliently and eccentrically connected to said closure plate for moving the latter normally to said planar wall and into positively closed position across said wall aperture and for moving said closure plate axially away from said wall aperture and thereafter laterally thereof to provide complete unobstruction of the latter.

5. Air lock apparatus adapted to be sealingly disposed across a wall aperture of a vacuum vessel for providing access to the interior thereof under a plurality of vacuum conditions, said apparatus comprising a generally rectangular open-sided housing, an aperture in said housing opposite said open side and in alignment with said wall aperture when said housing is in place, an elongated probe disposed in said tubular portion, a vertically slotted closure plate for said

wall aperture, and means including a rigid shaft extending through another wall of said housing and having an eccentric terminal portion of reduced diameter extending through the vertical slot of said closure plate for moving the latter rectilinearly into closed position across said wall aperture and for moving said closure plate rectilinearly away from said wall aperture and thereafter laterally thereof to provide complete unobstruction of the latter.

6. Air lock apparatus adapted to be sealingly disposed across a wall aperture of a vacuum vessel for providing access to the interior thereof under a plurality of vacuum conditions, said apparatus comprising a generally rectangular, open-sided housing, an aperture in said housing opposite said open side and in alignment with said wall aperture when said housing is in place, a closure plate for said wall aperture, an elongated bearing extending outwardly from another wall of said housing and having a cylindrical bore therein, an annular chevron type seal disposed in said bearing and surrounding said bore, a cylindrically bored gland nut threaded into said bearing and into compressive relation with said seal and means including a shaft extending from outside said housing through said nut, seal and bearing and having an eccentric and resiliently biased slot-type connection to said closure plate for moving the latter rectilinearly into positively closed position across said wall aperture and for moving said closure plate rectilinearly away from said wall aperture and thereafter laterally thereof to provide complete unobstruction of the latter.

7. The combination of elements recited in claim 6 and wherein the dimensions of said bearing, seal and nut axially of said shaft exceed the portion of the latter disposed within said housing in the closed position of said closure plate.

ROBERT T. AVERY.
